UNITED STATES PATENT OFFICE.

ROY X. TUTTLE, OF BATTLE CREEK, MICHIGAN.

DESIGN FOR A PAPER WEIGHT.

60,887.

Specification for Design. Patented Apr. 18, 1922.

Application filed February 14, 1921. Serial No. 445,003. Term of patent 3½ years.

To all whom it may concern:

Be it known that I, Roy X. TUTTLE, a citizen of the United States, and a resident of Battle Creek, county of Calhoun, State of Michigan, have invented a new, original, and ornamental Design for Paper Weights, of which the following is a specification, reference being had to the accompanying drawing, forming a part thereof, in which—

The figure is a front perspective view of a paper weight.

I claim:

The ornamental design for a paper weight, as shown.

ROY X. TUTTLE.
